UNITED STATES PATENT OFFICE.

DAVID M. BURNS AND ALEXANDER B. BURNS, OF GREENBAY, WISCONSIN.

BOILER OR WATER-HEATER.

SPECIFICATION forming part of Letters Patent No. 707,203, dated August 19, 1902.

Application filed May 5, 1902. Serial No. 105,952. (No model.)

To all whom it may concern:

Be it known that we, DAVID M. BURNS and ALEXANDER B. BURNS, citizens of the United States, and residents of Greenbay, in the county of Brown and State of Wisconsin, have invented certain new and useful Improvements in Boilers or Water-Heaters; and we do hereby declare that the following is a full, clear, and exact description thereof.

10 Our invention has for its object to provide simple, economical, and durable boilers and water-heaters that can be readily cleaned, said invention consisting in certain peculiarities of construction and combination of parts 15 particularly set forth with reference to the accompanying drawings and subsequently claimed.

Figure 1 of the drawings represents a vertical section view of a boiler or water-heater 20 in accordance with our invention, this view being indicated by line 1 1 in the third figure; Fig. 2, a partly-sectional elevation of the apparatus indicated by lines 2 2 in said third figure, and Fig. 3 a horizontal section view indicated by lines 3 3 in the first figure.

Referring by letter to the drawings, A indicates a cylindrical shell, and B C opposite angular boxes that are partly within the shell, these boxes being of greater length than depth 30 and located approximately midway between the extremities of said shell. Built in shell A, central of same below boxes B C, is a fire-chamber D, and ash-pit draft-space is provided below the fire-chamber, the diameter of 35 said fire-chamber being such that water-space is had between it and the aforesaid shell. Spacers b on bolts connecting the shell and walls of the fire-chamber serve to brace said walls.

40 Fire-chamber and ash-pit doors E F have hinge connection with frames E' F', bolted to shell A, and boxes B C have hinged doors B' C', each provided with pivotal latches c, engageable with keepers d, extending from the 45 corresponding box.

Shell A is provided with a lower inlet-nipple e and upper outlet-nipple f for connection with pipes, and an upper manhole of said shell is closed by a plate G on pin g, that extends through a yoke H and engages a clamp-

nut h, the ends of the yoke being in opposition to the aforesaid shell.

Midway of its length box B is partitioned by a baffle-plate I, and a similar plate J is arranged in box C at a greater elevation. The 55 door of each box is provided with inner flanges i, that extend over and under the baffle-plate in said box when said door is closed to thereby form a smoke-tight joint.

Pipes K lead from the top of fire-chamber 60 D into the lower compartment of box B, and products of combustion pass from this compartment through tiers of flues L into the lower major compartment of box C, then through tiers of flues M into the upper compartment of box B, and from thence through tiers of flues N into the upper minor compartment of box C, one end of this compartment being open and connected by a pipe P or otherwise with a smoke-stack. 70

From the foregoing it will be understood that water in shell A is around and over the fire-chamber, the pipes K, flues L M N, and so much of the boxes B C as extend into said shell being submerged, whereby a very considerable radiating-surface is exposed to said water to rapidly heat the same, the products of combustion being utilized to the best advantage. 75

With the exception of the doors, frames, 80 nipples, manhole-closure, and fire-chamber grate the heater is preferably of boiler-plate in water-tight union. The doors B' C' are practically sides of boxes B C opposite terminals of the flues aforesaid and being swung 85 open said boxes and flues may be readily cleaned. Access to pipes K is also possible through box B when the door of same is open.

Having thus described our invention, what we claim as new, and desire to secure by Letters Patent, is— 90

1. A boiler or water-heater comprising a cylindrical shell, boxes extending into the shell and provided with outer doors, flues in tiers connecting the boxes, a baffle-plate dividing one of the boxes into approximately equal upper and lower compartments, a similar plate in the other box at a greater elevation than the plate aforesaid, the minor upper compartment of the latter box being open 95 100

at one end for communication with a smoke-stack, a fire-chamber of less diameter than said shell built therein central of same, and pipes, leading from the fire-chamber into the 5 lower compartment of the box aforesaid.

2. A boiler or water-heater comprising a cylindrical shell, boxes extending into the shell and provided with outer doors, flues in tiers connecting the boxes, a baffle-plate dividing one of the boxes into approximately 10 equal upper and lower compartments, a similar plate in the other box at a greater elevation than the plate aforesaid, the minor upper compartment of the latter box being open 15 at one end for communication with a smoke-

stack, flanges on the box-doors arranged to lap the baffle-plates, a fire-chamber of less diameter than said shell built therein central of same, and pipes leading from the fire-chamber into the lower compartment of the first 20 aforesaid box.

In testimony that we claim the foregoing we have hereunto set our hands, at Greenbay, in the county of Brown and State of Wisconsin, in the presence of two witnesses.

DAVID M. BURNS.

ALEXANDER B. BURNS.
